UNITED STATES PATENT OFFICE

HEZEKIAH W. CARROLL, JR., OF HOBOKEN, NEW JERSEY, ASSIGNOR TO AUTOGRAPHIC REGISTER COMPANY, OF HOBOKEN, NEW JERSEY, A CORPORATION OF NEW JERSEY

MANIFOLDING MACHINE

Application filed February 21, 1927. Serial No. 162,697.

This invention relates to manifolding machines, and more particularly to the type of manifolding machine adapted to store a record copy within a suitable compartment provided for the purpose.

Heretofore, many attempts have been made to provide a record-storing device by means of which previously zig-zag folded record forms might refold in the record compartment to provide a smooth pack or pile therein. But, with these proposals it has been found that due to variations in paper qualities and other changing characteristics such as atmospheric condition, these record tickets would not invariably refold properly in the record compartment.

It has also been discovered, in connection with registers of the kind named, both the type in which the record strip is cut into separate record tickets and the type in which the record strip is caused to refold in zig-zag fashion, that the separation of the record strip from the worksheets, which are issued from the machine, greatly facilitates the control and positioning of the record tickets in the record compartment. To accomplish this, the present invention provides a separator which is located between the feed and pressure rollers and is made so thin and of such hard material as to occupy very little space between the issue and record ticket. Preferably, the separator blade is pivotally mounted so that it may accommodate itself to the rise and fall movements of the paper in advancing, as for instance when folded portions of the strip approach the bight of the feed and pressure rollers.

Other objects and advantages will herein-after appear.

In the accompanying drawings which show one form of the present invention, that at present preferred—

Figure 1 is a sectional view of a portion of a manifolding machine showing the record compartment and the refolding means therein made in accordance with the present invention.

Fig. 2 is a detailed perspective view of a portion of the refolding mechanism shown in Fig. 1.

Fig. 3 is an enlarged side sectional view of the feed mechanism, showing the improved separator provided by the present invention, and the manner in which it separates the sheets in use.

Fig. 4 is a side sectional view similar to Fig. 1, but showing one of the positions that the piled-up record strip may assume in the operation of the device.

Fig. 5 is a plan view of the separator of the present invention showing the related parts.

In the drawings, the delivery end portion only of the manifolding machine is shown, because only that part is needed to satisfactorily explain the application of the present invention thereto. At the delivery end of the manifolding machine, there is as usual provided feed rollers 10 and pressure rollers 11, the latter being mounted in floating bracket 12, whose lower ends are provided with springs 13 anchored at 14 on the side plates 15 of the manifolding machine, so that the pressure rollers 11 bear against the feed rollers 10 with sufficient pressure to advance the issue-strips 16 and the record-strip 17. Both the issue-strips 16 and the record-strip 17 before passing between the feed rollers 20 and pressure rollers 11 are drawn over a platen 18 upon which the writing operation is performed. From the platen the strips 16 and 17 pass under a hood 19 for the pressure roller, and then at the other side of the feed mechanism the issue-strips 16 are deflected upwardly out through an opening 20 constituted by the tearing-off edge 21 forming part of the hood 19 and a portion 22 of a top plate or cover 23 for the record supply compartment 24.

The record-strip 17 does not pass out through the opening 20 but extends downwardly under the portion 22 of the top plate 23 into the record compartment 24, where, as below described, it is caused by mechanism to refold upon pre-existing perforated and folded lines. These lines, as usual, mark the ends of each form on the issue and record-strips 16 and 17. The issue-strips, which extend out through the opening 20, are as usual severed from the machine by drawing the

perforated lines on the strips over the tearing-off bar 21 after the strips have been fed out a form length. The behavior of the record strip 17 in the record compartment will 5 be described below.

Before doing this, however, attention is called to the provision by the present invention of improved means for insuring the certain and complete separation of the issue 10 and record strips as they are passing through the feed mechanism of the machine so as to prevent the perforated and folded portions of the one set of strips from dragging on the other and to prevent said portions of the 15 strips from creeping up into the spaces 27 and 28 which exist between the hood 19 and the pressure roller 11.

This separator comprises a thin, hard sheet-metal plate 30 having trunnions 31 at 20 the forward end of its side margin which engage holes in the brackets 12 carrying the pressure roller 11. The trunnions 31 and the holes therefor are so located in the separator plate 30 and the bracket 12 respectively, that 25 the separator plate 30 will lie in a plane coinciding substantially with the bight of the feed rollers 10 and the pressure rollers 11, and so that the plate extends rearwardly to engage and smooth out the perforated and 30 folded portion of the issue-strips 16 and the record-strip 17 and separate the one from the other, the issue-strips 16 going over the plate 30 while the record-strip 17 is directed under the plate 30. The plate 30 is provided 35 with cut out portions 33 in the vicinity of the feed rollers 10 and pressure rollers 11 so as to permit the issue-strips 16 to be deflected downwardly and the record-strip 17 to be deflected upwardly into the apertures 33 40 where said strips engage each other and by means of the rotation of the feed rollers 10 and pressure rollers 11 and the friction produced therebetween are caused to feed when such operation is intended.

45 At its front end, the separating plate 30 functions to prevent the issue-strips 16 from being dragged down into the record compartment under the portion 22 of the top plate 23, because at this point the issue-strips 16 are 50 separated from the record-strip 17 and, moreover, there is very little space left between the portion 22 under which the record strip travels and the front end of the separating plate 30 into which the issue-strips could 55 pass.

The separating plate 30 described above may advantageously be used in any type of manifolding machine whether the record-strip is retained in the machine or not. However, it is particularly advantageous in case 60 where the record-strip is liable to meet with some obstacle against which it must be pushed or by reason of which it must flex one way or the other. Hence, it is extremely advantageous 65 to use the separator plate in connec-

tion with manifolding machines of the record-storing type in which the record-strip usually, and in accordance with the present invention, actually does meet with some resistances or retarding action in being fed 70 into the record compartment.

Having described the way in which the record-strip and issue-strips are separated in accordance with this invention, the refolding 75 mechanism will now be described.

It has been found in practice that when the record compartment 25 is provided with no mechanism of any kind, and there are no deflectors or other means for handling the record-strip, the previously folded and perforated record-strips fed from a supply compartment as indicated at S by the feed mechanism, upon entering the record compartment and being allowed absolute freedom therein, might refold of its own accord and continue to do so for some little time. But before long, the strips get balled-up and do not fold upon the previously folded and perforated lines. The reasons for this erratic 80 operation of the strip are many, a slight variation in quality of the paper or a slight variation in depth of the perforations on the folded line or a slight inaccuracy in the fold along the line of perforations might cause 85 this sudden change in the action of the paper. 90

Hence, means have been provided, heretofore, for the purpose of assisting the record-strip so that, even if the tendency to fold be very slight, the assisting mechanism will insure the fold at the proper place. Some 100 of these previously proposed devices have been found to materially reduce the danger of balling-up the record strip in the record compartment. Yet, it has been found that even with such proposals occasionally the 105 record strip would not fold as it was intended along the said folded and perforated lines, but would curl up in the machine, and, finally, due to the accumulation of paper immediately in front of the delivery side of the 110 feed rollers cause the machine to jam.

The present invention, however, avoids this danger of the record-strip balling-up in the record compartment so long as there is no tear or other serious damage in the record-strip itself before it gets to the record compartment.

This is accomplished, according to the present invention, by providing means which cause the record-strip in the record compartment to either fold accurately on the line or to assume an unusual position which experiments have shown to be the most natural position for causing the strip to refold. The means provided for this purpose by the present invention comprise a supporting plate 34 hinged at 35 to the top plate or cover 23 of the record compartment 24. This supporting plate is shown in detail in Fig. 2, and has at 120 its lower end a rolled part 36 which prevents 125 its lower end a rolled part 36 which prevents 130

the supporting plate from tearing the record-strip or from being caught accidentally thereon.

This supporting plate 34 is located directly in the path of the record-strip 17 as it is issued from the feed mechanism comprising the feed rollers 10 and pressure rollers 11, and in this position it deflects downwardly the leading edge of the record-strip so that the same will engage the bottom plate 24' of the record compartment 24. If the folds between the form lengths of the record-strip 17 are sharp and there is no peculiar characteristics above the paper to prevent easy folding 10 of the record-strip along the folded line, the record-strip will pass under the supporting plate 34 and assume its natural folded position in the supply compartment, as shown in full lines in Fig. 1, when one form is fed, 15 and the position shown in dot-and-dash lines 37 shown in Fig. 1 when the next form is fed. The full lines show the position the strip occupies when the record-strip is folded to the right as seen in Fig. 1, and the dot-and-dash 20 lines 37 indicate the position the strip will be in when the next form length of the record-strip is fed. The fold 38 of the record-strip shown in Fig. 1, will then lie down on the pile 39 while the fold 40, which is up near the feed 25 mechanism see Fig. 1, will lie at 41 on the pile 39.

When, however, a fold is reached which is not so sharp and where the tendency for the sheets to fold by falling freely and passing 25 under the supporting plate 34 does not exist, the record strip is held-up by the supporting plate 34 and is not permitted to fall. Thereafter, as the forms are fed, the record-strip is folded zig-zag in a curved or curvilinear 30 form, the upper end being near the top of the supporting plate 34 and the lower end resting against a wall 42 provided in the record compartment, as shown in Fig. 4. Further referring to this figure, the full lines 35 show the position which the record-strip assumes when the fold 38 is against the pile 44 supported by the supporting plate 34 and the fold 40 in the reverse direction is adjacent the delivery side of the feed-rollers 10 and pressure-rollers 11. When the next form length 40 of the record-strip is fed by the feed mechanism, the fold 40 is carried down until it lies at 46 as shown by the dot-and-dash lines 47 where the fold 46 is against the plate 42.

Experience has shown that the record-strip 17 folds more accurately and positively while in the inclined curvilinear form shown in Fig. 4 with the folds 38 and 41 located at substantially the same distance from the delivery side of the feed mechanism than by merely depending on the strips falling in proper position by themselves.

When the depth of the curved pile 44 of the folded record-strips increases, the weight 45 and tension thereof moves the supporting

plate 34 in the direction of the arrow shown in Fig. 4, and, as soon as the weight and tension become sufficient, the plate 34 slips up and allows the pile 44 to drop upon the previously folded pile 39', Fig. 4. Thereafter, 70 as the advancement of the strips continues, the folded record strip 17 may slip by the supporting plate 34 or it may not, depending upon the conditions of the folds, but eventually conditions will arise wherein the 75 folded record-strip does not pass the supporting plate 34 and then the record strip continues to pile up against the plate 34 until the condition shown in Fig. 4 exists.

Upon discovery that some parts of the 80 record-strip refold better in a curved position, such as shown in Fig. 4, experiments were made to ascertain whether it would be advantageous to cause the record-strip to assume this position from the very beginning. 85 However, these experiments have shown that when the record-strip 17 piles up against the supporting plate 34 to a pile of sufficient thickness for handling a pack of strips, enough room is not left between the top of 90 the pile and the feed mechanism for proper refolding.

By making the supporting plate 34 of the desired weight or by suitably biasing it by spring means and by changing its position 95 with relation to the feed mechanism as permitted by a screw 60 located in a slot 61 in a plate 62 on which the supporting plate 34 is pivotally mounted, the thickness of the pile 44, which is supported by the plate 34, 100 may be accurately predetermined, and hence by so arranging the supporting plate 34 it can be made to permit an escape of the pile 44 before the top of the pile too closely approaches the delivery side of the feed mechanism. 105

To assist the record-strip in folding to the right, as seen in Figs. 1 and 4, and to cause the folded edges adjacent the backing plate 42 to lie close thereto, the plate 42 is provided 110 with a deflector 48 which extends upwardly towards the pivot point of the supporting plate 34 for about half the distance between that point and the backing plate 42 and then extends backwardly and upwardly toward the feed-rollers 10. Adjacent the feed rollers 10, the deflector 48 is slotted or cut-out to provide fingers 49 to extend between the feed-rollers 10 so that it may receive and 115 guide the record strip 17 as it leaves the feed-rollers.

For the purpose of determining the position of the pile 39 and 39' in the record compartment, there is provided a front plate 51 against which the right-hand-fold edges 125 of the record-strip engage.

Otherwise, the record compartment may be of any suitable form or style having a front end 52 and a sliding or pivoted top door 23 as in the form shown. When the 130

door 23, by means of which access is had to the pile, is hinged as at 53 it is preferable to have the portion 22 thereto which extends under the tearing off edge 21 of the hood 5 hinged thereto at 54, so that, when the door is closed the portion 22 is swung downwardly on the hinge 54 enabling the leading edge of the portion 22 to extend under the tearing-off bar 21, thereafter the movement of the 10 door is completed and the portions 22 align with the main portions of the door 23.

To aid in deflecting the record strip 17 and to prevent the perforated and folded margins of the forms from catching on the hinge 54, 15 a deflector plate 55 is secured to the front edge of the portion 22.

Of course, if desired, the supporting plate 34 may be hinged to the side plate 56 of the record compartment. However, it is advantageous to have it hinged on the door 23, because by such an arrangement when the door 23 is swung upwardly to give access to the record compartment the supporting plate 34 is automatically withdrawn therefrom, 25 and free access is had to the folded record strip 17 in the record compartment.

Variations and modifications may be made within the scope of this invention and portions of the improvements may be used without others.

Having thus described the invention, what is claimed as new and for which it is desired to obtain Letters Patent, is:

1. In a manifolding machine having a 35 platen over which worksheets are fed; and means for feeding said worksheets over the platen: means located at said feeding means for separating certain of the worksheets from others as they approach and leave said 40 feeding means.

2. In a manifolding machine having a platen over which a plurality of previously 45 perforated and creased webs are adapted to be fed; and means for feeding said webs over said platen, said feeding means comprising a pair of cooperating feed rollers: means located in the plane of the line of contact of said feed rollers for separating certain of said previously perforated and folded webs as they 50 approach and leave the feed rollers.

3. In a manifolding machine having a platen over which a plurality of webs are fed; and cooperating feed rollers for advancing said webs over said platen: a thin hard 55 metal plate located in the plane of the line of contact of, and adjacent said feed rollers with portions at each side of the feed rollers to separate certain of said webs from others as they approach and leave the feed rollers.

4. In a manifolding machine having a platen over which a plurality of webs are fed; and cooperating feed rollers for advancing said webs over the platen; a thin separator located in the plane of the line of contact of, and adjacent said feed rollers with

portions at each side of the feed rollers for separating certain of said webs from others as they approach and leave the feed rollers.

5. In a manifolding machine having a platen over which a plurality of webs are fed; 70 feed rollers for advancing said webs; pressure rollers for cooperating with said feed rollers to advance said webs; and a pair of brackets for carrying said pressure rollers: a thin metal plate pivotally mounted in said 75 bracket and located in the plane of the line of contact of, and adjacent said feed rollers with portions at each side of the feed rollers for separating said webs as they approach and leave the feed rollers and pressure rollers. 80

6. In a manifolding machine having a platen over which a plurality of webs are fed; and cooperating feed rollers for advancing said webs over the platen: a thin metal strip 85 located in the plane of the line of contact of, and adjacent said feed rollers with portions at each side of the feed rollers to direct certain of said strips upwardly and certain of said strips downwardly as they approach the feed rollers, said plate being provided with 90 apertures through which the upwardly directed webs are pressed downwardly into contact with the downwardly deflected webs which are pressed upwardly bringing the webs into contact with each other and the 95 feed rollers for strip-advancement.

7. In a manifolding machine having a platen over which a plurality of webs are fed; cooperating feed rollers for advancing said webs over the platen; and a hood for 100 covering part of said feed mechanism: means located in the plane of the line of contact of said feed rollers and extending across the space necessarily provided between said feed mechanism and said hood. 105

8. In a manifolding machine having a platen over which a plurality of webs is fed; and cooperating feed rollers for advancing said webs over the platen: means pivotally mounted in the plane of the line of contact 110 of said feed rollers for separating the webs in the vicinity of the feed rollers.

9. In a manifolding machine having a platen over which a plurality of webs is fed; feed rollers for advancing said webs over the 115 platen; pressure rollers for holding the webs in contact with the feed rollers; and brackets carrying said pressure rollers and movable to release the pressure between the pressure rollers and the feed rollers: a thin metal plate 120 pivotally mounted in said bracket for separating the webs as they approach and leave the feed rollers and the pressure rollers.

Signed at Hoboken, in the county of Hudson and State of New Jersey, this 16th day 125 of February, 1927.

HEZEKIAH W. CARROLL, Jr.
